UNITED STATES PATENT OFFICE.

THOMAS E. MURRAY, OF NEW YORK, N. Y.

METHOD OF MAKING METAL RINGS.

1,267,251.

Specification of Letters Patent. Patented May 21, 1918.

Application filed November 1, 1917. Serial No. 199,776.

To all whom it may concern:

Be it known that I, THOMAS E. MURRAY, a citizen of the United States, residing at New York, in the county of New York and 5 State of New York, have invented a certain new and useful Improvement in Methods of Making Metal Rings, of which the following is a specification.

The invention is a method of making metal 10 rings from flat bars or plates of metal in such a way as that the ring when completed will be truly circular. The invention is more especially suited to the making of rings which form parts of structures, and therefore require accurate configuration. Such 15 rings, for example, may be used within or without cylindrical shells or casings of sheet metal to serve as supports or strengthening ribs. The usual mode of making a ring of 20 this kind is to draw a flat plate into a cup having its cylindrical wall of suitable width for the desired ring. The bottom of the cup is then cut off, leaving the wall in annular form. As repeated drawing operations may 25 be necessary, and allowance must be made for consequent diminutions in thickness of the plate, and the removed bottom may be of no immediate utility, this proceeding is expensive, difficult and requires much care 30 and calculation to insure reasonable accuracy.

I select two plates or bars of suitable thickness and width. On each plate I lay off a middle portion equal in length to that 35 of a semi-circle of the desired ring, and also two end portions respectively at opposite ends of said middle portions. If beyond these end portions, other portions of the bars or plates still remain, such other portions are 40 to be removed. I then bend the middle portion only of each ring in a true semi-circle, so that from the extremities of the two semi-circular ring sections the end portions will extend straight and parallel. I then seat 45 the plates, bent as described, in recesses in suitable electrodes, so that said end portions will protrude and face one another. Then by moving one or both electrodes, I press the said ends strongly together, and establish 50 a welding electrical current to said electrodes. This renders the protruding end portions of the ring sections plastic, so that the pressure continuing, the metal of said end portions is extruded from the joint until 55 the extremities of the truly semi-circular ring sections come together, thus completing

the ring. The extruded metal at the joint is afterward ground off, or otherwise taken away, leaving the surfaces smooth.

In the drawings the size of the straight 60 end portions with respect to the middle or semi-circular portions of the ring sections is purposely exaggerated for the sake of clearness.

In the accompanying drawings— 65

Figure 1 is a plan view of the two plates from which the ring sections are made. Fig. 2 is a plan view, showing the sections after bending seated in separated electrodes. Fig. 3 shows the sections welded together and 70 still seated in said electrodes. Fig. 4 is a section on the line x, x of Fig. 2. Fig. 5 is an edge view of the completed ring.

Similar letters and numbers of reference 75 indicate like parts.

A and B, Fig. 1, are two flat metal plates or bars alike in dimensions, from which the ring is to be made. On plate A, I lay off a middle portion 1, 2 equal in length to the semi-circumference of the desired ring, 80 and on the plate B, a like middle portion 3, 4. Beyond each end of middle portion 1, 2, I lay off an end portion 2, 5 and 1, 6, and beyond each end of middle portion 3, 4, I lay off similar end portions 3, 7 and 4, 8. 85

I bend the middle portion 1, 2 of the plate A to form a semi-circular ring section, and I bend the middle portion 3, 4 of plate B to form a like semi-circular ring section. The end portions 1, 6; 2, 5; 3, 7 and 4, 8 will 90 then be parallel and extend beyond the ends of said semi-circular sections.

I place the semi-circular sections in semi-circular recesses in electrodes C, D, as shown in Fig. 2, so that said end portions will 95 protrude beyond the opposing faces of said electrodes. By moving either electrode, or both of them, I press said end portions together. The welding current is also established.

Said end portions are thus fused, and as 100 the pressure continues, are melted and extruded at the joints until the extremities of semi-circular section 1, 2 meet the extremities of semi-circular section 3, 4, when the ring becomes completed.

The length of end portions 2, 5; 1, 6; 105 3, 7 and 4, 8 will depend upon the amount of metal which may be determined as the minimum necessary to insure close union of the semi-circular sections at the joints. 110 Whatever fused metal is extruded is to be cut or ground off in any suitable way.

It is to be noted that said end portions are formed on both semi-circular sections, and not solely on one of them. If, for example, in Fig. 1 the end portions 1, 6 and 5, 2, 5 were retained, and the end portions 3, 7 and 4, 8 on the opposing semi-circular section were omitted, it would not be practicable to produce a truly circular ring, for the reason that when said end portions 1, 6 and 2, 5 met the extremities of semi-circular section 3, 4, the fusing of the metal would take place partly in said end portions and partly in said semi-circular section, and the latter would then cease to be a semi-circle by just the amount of metal consumed. Hence the ends of said sections would not register, and a truly circular ring would not result.

The meeting of the opposing faces of the electrodes after the welding of the ring is completed operates as a stop to prevent further approximation of said electrodes. In order to prevent passage of current between the contact faces of said electrodes after the ring is welded, a layer 9 of insulating ma-

terial may be secured upon the face of one of said electrodes.

I claim:

The method of making a metal ring, which consists in, first, laying off on each of two flat plates middle portions 1, 2 and 3, 4, each equal in length to a semi-circumference of said ring, and, at the extremities of said laid off middle portions, end portions 1, 6; 2, 5; 3, 7 and 4, 8; second, bending said middle portions to form semi-circular ring sections; third, pressing said end portions of said sections together and electrically heating the same until the metal of said end portions is rendered plastic and extruded at the joints and the extremities of said semi-circular ring sections come together and are united.

In testimony whereof I have affixed my signature in presence of two witnesses.

THOMAS E. MURRAY.
